UNITED STATES PATENT OFFICE

THOMAS P. JAKOBSON, OF LOS ANGELES, CALIFORNIA, ASSIGNOR OF ONE-HALF TO
EMELIA M. KLING, OF LOS ANGELES, CALIFORNIA

MUSIC LEAF TURNER

Application filed March 25, 1929. Serial No. 349,843.

This invention relates to new and useful improvements in music leaf turners, and particularly to turners which are associated with music stands.

5 One object of the invention is to provide a device of this character which is simple in construction, and which may be easily folded, to occupy a small space, when not in use.

Another object is to provide a device of this 10 character which includes novel means for holding those portions and leaves of a book which are to be turned, thus leaving the remainder of the leaves free to be turned.

Another object is to provide a device of this 15 character which is equipped with novel means whereby the music supporting portion of the stand may be firmly clamped on the music shelf or ledge of a piano.

A further object is to provide a device of this 20 character which includes means for maintaining the rack in proper position against the back-board of the music ledge of a piano.

Other objects and advantages will be apparent from the following description when 25 taken in connection with the accompanying drawings.

In the drawings:

Figure 1 is a front elevation of the device as applied to the music ledge of a piano.

30 Figure 2 is a vertical sectional detail view on the line 2—2 of Figure 1.

Figure 3 is a front elevation of the device in folded position.

Figure 4 is a vertical sectional view on the 35 line 4—4 of Figure 1.

Figure 5 is a horizontal sectional view on the line 5—5 of Figure 1.

Referring to the accompanying drawings, 40 there is shown a music rack which includes the central upwardly extending flat strip 10, to the opposite sides of which are pivotally connected the music ledge members 11, and the laterally extending braces 12. The braces 12 are formed with longitudinal slots 13, which receive therethrough the bolts 14, carried by the intermediate portions of the 45 central strip 10, whereby said braces may be slid inwardly and outwardly, for the purpose of adjusting the rack for music pages of different widths. In the outer end of each

of the braces 12 there is formed a longitudinal slot 15, and disposed through the slot, and through the vertical side bar 16, of the rack, as well as through the outer end of the brace arm 17, which has its other end pivotally connected to the central strip 10, is a pivot member 18. The bolt 14 is provided with the winged nut 19, by means of which the arms 12 may be held in their adjusted positions. Slidable longitudinally on the outer portion of each of the braces 12 is a sleeve 20, which is provided with a fingerpiece 21, for cooperation with the fingerpiece of the pivoted spring pressed jaw 22. This jaw has a transverse bar 23, on its outer end, for cooperation with the brace 12, to clamp those pages of a book of music, which are not to be turned by the device, the sleeve being arranged to be moved on the brace to accommodate books, or sheet music of different widths, as will be clearly understood.

To fold the rack portion of the stand, the operator grasps the music ledge members and swings them upwardly until they lie in superimposed relation to the central strip 10. The upward movement of the members 11 75 draws the brace arms 17 upwardly, also, and at the same time swings the vertical side bars 16 into close relation to the members 11 and the strip 10, so that the said bars extend in an upward direction.

Mounted on the upper and lower portions of the rear face of the central strip 10 are the members 24, each having a plurality of vertically disposed tubular sockets 25. Disposed in each of the tubular sockets 25 is the vertical arm of a right-angular wire member 26, the other arm extending in parallel relation to the music ledge members of the rack, as clearly seen in Figure 1, of the drawings. Telescoped on the other arms of the members 26 are the tubular members 27, a flat strip 28 having its upper and lower ends secured to the other ends of an upper and lower tubular member, whereby to provide a rectangular leaf turning frame. These frames are adapted to be turned by any well known means, which it is not thought necessary to illustrate. Carried by the flat strip 28 are the spring clips 29, which are adapted to

grip the outer vertical edge of a music page. When the rack is to be folded, the frames 28—26 are removed therefrom, by withdrawing the tubular members 27 from the members 26, and then slipping the members 26 from the tubular sockets 25.

Secured to the lower face of each of the music ledge members 11 is a spring jaw clamp 30, which is lined with some soft material, whereby to prevent marring of the surface of the music ledge of a piano, not shown. These clamps serve to hold the music rack portion of the music stand, when removed from the floor supporting portion, whereby to adapt the device for turning the pages of music for a performer, at the piano. To serve as an additional strengthening means for the device, when used on the music rack of a piano, there is provided a vertical member 31, which has a reduced end engaged in a socket member 32, carried by the rear face of the central strip 10. The member 31 extends upwardly beyond the upper end of the strip 10, and has the soft material attached thereto on the face which engages the back-board of the music rack of the piano.

Mounted on the forward face of the strip 10, adjacent the upper and lower ends thereof, are the outstanding brackets 32', each formed with an opening 33 for the reception of the upper and lower ends of the wire rod 34. The intermediate portion of said rod 34 carries a small clip 35 which is adapted to receive and hold the inner edges of the inner loose leaf of a piece of sheet music, thereby serving as the hinge for such leaf.

As seen in Figure 2, the rear face of the strip or member 10 is provided with a loop 36 which is adapted to receive the upper flat end of the stem of the ordinary floor stand of a music rack, when such rack is to be used by the player of some instrument other than the piano.

While I have illustrated the arms 12 as connecting with the member 10 by means of separate pins or screws 14, I wish it understood that both arms may be connected to said member by a single pin or screw, without exceeding the scope of the invention or claims.

What is claimed is:

1. A foldable music leaf turning rack including a central member, ledge members pivoted thereto, laterally extending arms slidably and pivotally connected with the central member, brace arms pivotally connected with the central member between the lateral arms and the ledge members, vertical members pivotally mounted on the outer ends of the ledge members and each having a pivot member intermediate its ends engaged in the outer end of a brace arm, each of said lateral arms being slidably engaged with one of said pivots, leaf turning frames supported on said central member, and a grip-

ping jaw slidably adjustable on each of the lateral arms for cooperation with said arm for gripping and holding pages not to be turned.

2. A foldable music leaf turning rack including a vertical central member, ledge members pivotally mounted on the central member, lateral arms slidably and pivotally connected to opposite sides of the central member, vertical members pivotally connected with the outer ends of the ledge members and each having a pivot member intermediate its ends, brace arms each pivotally connected at one end with the central member adjacent the ledge members and having its other end connected with the pivot of said vertical member, the outer ends of the lateral arms being slotted to receive said pivot members, leaf turning frames removably mounted on the central member, and a leaf gripping clip slidably supported on each lateral arm having a transverse member cooperating with said arm to retain pages of music not to be turned.

In testimony whereof, I affix my signature. 90
THOMAS P. JAKOBSON.
